UNITED STATES PATENT OFFICE

132,763

DESIGN FOR A COUNTER COOKING APPLIANCE

Edwin A. Jones, Webster Groves, Mo., assignor to Majestic Manufacturing Co., St. Louis, Mo., a corporation of Missouri

Application October 10, 1941, Serial No. 103,710

Term of patent 14 years

To all whom it may concern:

Be it known that I, Edwin A. Jones, a citizen of the United States, residing in Webster Groves, St. Louis County, Missouri, have invented a new, original, and ornamental Design for a Counter Cooking Appliance, of which the following is a specification, reference being had to the accompanying drawing, forming part thereof, in which:

Fig. 1 is a front elevational view of a counter cooking appliance, showing my new design; and

Fig. 2 is a perspective view thereof.

The characteristic feature of my design resides in the particular configuration of the front portion of the article as shown in the drawing.

I claim:

The ornamental design for a counter cooking appliance, as shown and described.

EDWIN A. JONES.
